PENCIL.

1,353,352.

Specification of Letters Patent. Patented Sept. 21, 1920.

Application filed November 11, 1919. Serial No. 337,160.

To all whom it may concern:

Be it known that we, FRANK J. KRISTOFEK and HOWARD L. FISCHER, citizens of the United States, residing at St. Paul, in the 5 county of Ramsey and State of Minnesota, have invented a new and useful Improvement in Pencils, of which the following is a specification.

Our invention relates to a pencil, the operating parts of which are held collectively removable from the pencil barrel or shell so that a new marking lead can be inserted in position for use when the old lead is worn too short. When the operating parts of 15 our pencil are removed from the barrel by a simple operation, a new marking lead can readily be inserted in place for use while the pencil barrel, which is adapted to inclose the operating parts, is formed with an inner 20 smooth contour so that in the construction of the pencil no mechanism is secured rigidly in place in the barrel but rather allows the barrel to be formed of thin tubing by swaging the forward end into the desired conical 25 shape to simulate the writing end of a pencil while the rear end is swaged to receive a holding thread by very simple operations. In the making of a pencil it is important that it be of simple construction and of a 30 practical nature so that all the parts are formed exactly the same with ordinary dies, tools and swaging mechanism and without the necessity of each pencil being made by hand, especially where it is desired to manufacture the pencils for commercial purposes.

A feature of our invention is that by a suitable locking means the mechanism is held for operation in the pencil barrel and the rotatable operating head will propel the 40 lead out of the writing end of the barrel when turned toward the right while the operating mechanism will withdraw the lead when the head is turned to the left. A continued turning of the operating head to 45 the left will unlock the operating mechanism from the pencil barrel so that it can be withdrawn. This feature is important in accomplishing a natural result.

Further our pencil provides means for 50 conveniently holding extra marking leads so that when the mechanism is removed from the barrel a new marking lead can be readily engaged and inserted in the operating mechanism. The lead holding 55 means is so constructed that the free ends

of the extra marking leads will be automatically distended from the main parts or body of the operating mechanism to allow easy engagement of the same while upon inserting the operating mechanism into the barrel 60 the marking leads are drawn into close relation with the body of the operating mechanism to hold them in a collective position, freely insertible into the pencil barrel or ready to be withdrawn with the operating 65 mechanism.

Our invention further provides sockets for the extra leads, which are so constructed as to freely receive the extra marking leads to hold them therein, together with means 70 for holding the extra marking leads collectively slidable on the operating mechanism to project the free ends of the extra leads beyond the forward end of the operating mechanism when it is desired. 75

In the drawings forming part of this specification:

Figure 1 is a side view of our pencil, illustrating the barrel in longitudinal cross section. 80

Fig. 2 is a view of the operating mechanism and extra lead holding means, part of the mechanism being illustrated in cross section.

Fig. 3 illustrates an alternative construction of lead holding means for our pencil. 85

Fig. 4 is a detail of a portion of the construction illustrated in Fig. 3.

Fig. 5 is a detail of our pencil illustrating an alternative construction of lead holding 90 means.

Fig. 6 is a cross section of the pencil on the line 6-6 of Fig. 1.

The drawings illustrate our pencil A, which is designed to hold a marking lead 95 10 of a long, thin construction having a very small diameter. The barrel 11 of the pencil is formed of any suitable tubular material with a thin wall and the forward end 12 is swaged to a conical shape to simulate the writing end of an ordinary pencil, while an opening 13 is formed in the apex 100 of the conical end 12 of approximately the same size, shape or diameter as the marking lead 10.

The marking lead 10, when it is in position for use, is held axially in the pencil and in the operating mechanism B, which has a socket 14, to engage the rear or butt end 105 of the marking lead and which is secured 110

rigidly to the driving member 15. The socket 14 and member 15 are held freely 5 slidable in the tubular member 16 with the engaging edge 17 of the driving member extending through the longitudinally extending slot 18 formed in the member 16 so that the notches 19 in the edge 17 will engage the thread 20 formed in the tubular member 21. The tubular member 21 is positioned to surround the member 16 and the rear end of the same is rigidly secured to or 10 formed integral with the threaded locking head 22. The rear end of the member 16 extends through the rear end of the tubular threaded member 21 and is engaged by the pin 23, which is formed integral with the head 24, the pin 23 being soldered or rigidly attached to the inner end of the member 16 to rigidly secure the operating head 24 15 to the member 16. By means of a suitable collar 25, which is rigidly secured by solder or other suitable means, to the forward end of the tubular member 16, the tubular threaded member 21 with its operating head 22 is secured against longitudinal movement 20 but freely rotatable on the tubular operating member 16.

The member 16 is slightly larger in diameter than the marking leads 10 so that 30 the same can freely move in the member 16 when the marking lead 10 is held in position for writing in the pencil barrel 11, and to allow the marking lead to slide freely into the conical forward end 12 through the 35 opening 13 without any side pressure which might tend to break the very thin lead. This is an important feature of the invention, as it allows the marking lead to aline or adjust itself with the hole 13 in the pencil 40 barrel 11.

The operating mechanism B is inserted into the pencil barrel 11 with the threads 26 of the locking member 22 engaging the threads 27 in the rear of the pencil barrel 45 so that by screwing the member 22 tightly into the threads 27 the operating mechanism B will be locked in the pencil barrel 11 with the threaded member 21 held against rotation, while the operating head 24 is freely 50 rotatable to rotate the member 16 and cause the driving member 15 to be propelled in either direction in the same by engaging with the threads 20 to eject or withdraw the marking lead 10 from the writing end of the pencil A. The engaging end 17 of the 55 driving member 15 is held movable in the slot 18 free to follow the thread 20 so that the operation of the head 24 will move the member 15 along the thread 20.

60 Extra marking leads 10' are held in the sockets 28, which are formed on the band 29, while the band 29 engages the outer surface of the member 21 either frictionally or is rigidly attached thereto in any suitable 65 manner to hold the marking leads 10' in po-

sition in the pencil A. The sockets 28 are connected to the band by the flexible shanks 30 so that when the operating mechanism B is withdrawn from the pencil barrel the free ends of the marking leads will be automatically distended away from the body of the member 21 to allow them to be freely engaged and removed from the sockets 28 and after the old stub of the marking lead has been removed from the socket 14 a new 70 marking lead can be freely inserted therein. As the operating mechanism B is inserted into the barrel 11 of the pencil the spring sockets 28 will frictionally engage against the inner side of the same and draw 75 the extra leads 10' into close proximity to the body of the member 21 to hold the free ends of the same against engagement with the threads 27 and allow the extra leads to pass freely in and out of the barrel 11. 80

The barrel or casing 11 of the pencil A forms the outer wall of the magazine compartment for the extra marking lead 10', while the threaded member 21 of the lead propelling unit B forms the inner wall 90 thereof. Thus the lead propelling mechanism co-operates with the casing to form a magazine compartment about the mechanism B. When the lead propelling mechanism B is removed from the casing 11 the 95 entire contents of the magazine compartment is withdrawn from the pencil.

The outer ends of the sockets 28 are flared at 31 to form a larger opening in the receiving end of the socket to allow the leads 100 to be more easily inserted therein. This feature allows the extra leads to be easily inserted in the spring sockets 28.

The construction illustrated in Figs. 3 and 4 is of an angular spring socket member 105 32, which is formed of thin spring material and is split at 33 longitudinally so as to engage the threaded member 21 frictionally and to be freely and slidably held thereon. The extra marking leads 10' are held by 110 the spring member 32 in the corners or apexes 34 of the angular member 32. It is obvious that the spring socket member 32 can be triangular in general cross sectional shape with rounded apexes or of any other 115 suitable angular shape to form recesses between the member 21 and the member 32 to receive the ends of extra marking leads 10', while the spring construction of the member 32 allows the free ends of the extra leads 120 10' to be engaged and raised away from the body of the member 21 to withdraw the same from the spring socket member 32 without disturbing the rest of the marking leads held thereby and without breaking the marking lead engaged. This construction forms an inexpensive means of holding the extra marking leads.

Fig. 5 illustrates the tubular member 29 125 reversed in position on the member 21 and 130

freely slideable thereon, while the spring 5 sockets 28 are held by the spring shanks 30 in close proximity or parallel to the body of the member 21 to hold the marking leads 10' closely thereto. In this construction the member 29 is freely slideable on the member 21 so that the free ends of the marking leads can be projected beyond the forward end of the operating mechanism to withdraw any 15 of the same from the sockets 28 without interfering with the other mechanism.

The simple inexpensive construction of our pencil with its free operating parts tends to give a complete device of a very practical 15 nature and it will be readily seen that the construction of the same allows the operating parts of one pencil to be freely interchangeable with the operating parts, as a whole, with another pencil of the same construction. This will allow the use of the 20 same barrel 11 for holding a different or new operating mechanism B so that when a man purchases this pencil, if the operating mechanism B becomes inoperable or is defective he can readily secure a new one without inconvenience to the dealer and by retaining his own barrel or shell 11, which may have received some use. By this it 25 will be noted that the construction of our pencil will allow the interchanging of the operating mechanism with the barrels, a feature which is most desirable in a practical pencil.

In accordance with the patent statutes we 35 have described the principles of operation of our invention, together with the apparatus which we now consider to represent the best embodiment thereof, but we desire to have it understood that the construction 40 shown is only illustrative and that the invention can be carried out by other means and applied to uses other than those above set forth within the scope of the following claims.

45 We claim:

1. A pencil including a tubular barrel, means for propelling a marking lead in either direction, comprising, a threaded tubular member, a locking head rigidly attached to the rear of said threaded member, a lead receiving tubular member, a lead driving element having a lead receiving socket slidably held within said lead receiving member, said driving member being 50 adapted to engage the threads on said threaded member to propel a lead held in said socket, an operating head fixed to the rear end of said lead receiving member adjacent said locking head and a collar at the 55 forward end of said lead receiving member adapted to retain said threaded member on said lead receiving member against longitudinal movement and to support the forward 60 end of the same in said barrel.

65 2. A pencil including a hollow barrel, a

hollow conical forward end on said barrel, a lead propelling means adapted to be collectively removably held in said barrel, comprising, a hollow threaded member, a locking collar fixed to the rear end of said member, a longitudinally slotted hollow member extending through said threaded member, a lead driving element in said slotted hollow member, a head adjacent to said collar and fixed to the rear end of said slotted member and a collar connected to the forward end of said slotted member and adapted to support the forward ends of said threaded and slotted members in said hollow barrel.

3. A pencil comprising a tubular barrel having an open rear end, a lead propelling means removably held in said barrel, including, a tubular longitudinally slotted member, a lead driving member in said slotted member, an operating head formed on the rear end of said slotted member, a tubular threaded member through which said slotted member is adapted to extend, a locking head formed on said threaded member adjacent said operating head and a collar connected to and adapted to support the forward ends of said slotted and threaded members in said barrel.

4. A pencil including means for propelling a marking lead in either direction, a hollow barrel having a rear opening to receive said propelling means, said propelling means including two exposed operating heads adjacent each other, one rigidly fixed 100 to said propelling means and adapted to lock it in said barrel and the other adapted to operate said propelling means.

5. A pencil comprising the combination of a tubular barrel, a threaded open rear 105 end formed on said barrel, a threaded tubular member adapted to be contained in said barrel, a locking collar on the rear end of said threaded tubular member adapted to engage said threaded open end of said barrel, a longitudinally slotted tubular member extending through said threaded tubular member, an operating head secured to the rear end of said slotted member, a lead driving member in said slotted member and a 115 supporting collar connected to and adapted to support the forward ends of said slotted and threaded members respectively in said barrel.

6. A pencil having a barrel, a lead propelling means, a locking head rigidly connected to said propelling means and an operating head adjacent said locking head, said locking and operating heads being adapted to be engaged and rotated together to remove or insert said propelling means in said barrel.

7. A pencil having a barrel, a lead propelling means, a locking collar rigidly secured to said propelling means and an oper-

ating head for said propelling means adjacent said collar, said head and collar both being engaged and rotated together with said propelling means to remove said propelling means from said barrel.

8. A pencil including a barrel, a lead propelling means and resilient means adapted to automatically distend an extra marking lead from said propelling means when said propelling means is removed from said barrel.

9. A pencil comprising in combination a barrel, a lead propelling means and means adapted to hold one end of a series of extra marking leads to said propelling means, whereby the free ends of the extra marking leads will be distended away from said propelling means when removed from said barrel and be drawn collectively together adjacent said propelling means when inserted in said barrel.

10. A pencil including means adapted to hold a series of extra marking leads to automatically distend and collect the leads when said pencil is opened and closed respectively.

11. A pencil having a barrel, a lead propelling means and means adapted to hold one end of a series of extra marking leads collectively to said propelling means with the free ends of the extra leads extending toward the rear end of said propelling means to cause the collectively held ends of the leads to enter said barrel first when said propelling means is inserted in said barrel.

12. A pencil including a barrel, a lead propelling means and means adapted to hold a series of extra marking leads automatically distended or collectively drawn together about said propelling means when said propelling means is removed or inserted respectively in said barrel.

13. A pencil, comprising a barrel, a lead propelling means within the barrel and spaced therefrom to form a lead receiving magazine between the lead propelling means and the barrel and a closure on said lead propelling means for said magazine removably secured to said barrel to remove said propelling means in its operative entirety and open said magazine.

14. A pencil having within its body a lead propelling mechanism extending to the exterior of the pencil body, there being a space surrounding said mechanism within the body open at its upper end and form-

ing a circular magazine for reserve leads, the propelling mechanism extending to the exterior of the pencil body at its upper end, means integral with said propelling mechanism adapted to form a closure for the magazine detachably secured to the pencil body whereby leads within the magazine may be extracted, and means extending beyond the closure means for actuating the lead propelling mechanism.

15. A pencil having within its body a lead propelling mechanism extending to the exterior of the pencil body, there being a space surrounding said mechanism within the body open at one end and forming a magazine for reserve leads, means integral with said propelling mechanism detachably secured to the pencil body for forming a closure for the magazine whereby leads within the magazine may be extracted and means for actuating the lead propelling mechanism extending to the exterior of the lead propelling mechanism and pencil body at the open end of the magazine.

16. A pencil whose body is formed of a hollow casing, comprising a lead propelling means within the casing there being a space surrounding the lead propelling mechanism open at the upper end of the pencil and forming a magazine for reserve leads, means on said propelling mechanism extending exterior of the casing for detachably securing the lead propelling means in its entirety to the casing and forming a closure for said magazine and means for actuating the lead propelling mechanism extending to the exterior of the pencil body at its upper end, said propelling mechanism being detachably secured to the pencil body whereby leads may be removed from the magazine.

17. A pencil comprising a casing having an open end, a removable unit comprising means for gradually feeding the lead through the open end of the casing as the lead is worn away at the writing point, said unit being positioned in a manner to provide a lead receiving compartment about the unit within the casing, said casing forming the outer wall of the compartment, whereby the contents of the compartment is withdrawn from the casing when the unit is removed therefrom.
